HEAD FOR SPOOLS, REELS, OR SECTION BEAMS

Robert V. Olson, Attleboro, Mass., assignor to
Mossberg Pressed Steel Corporation, a corpora-
tion of Massachusetts

Application January 31, 1939, Serial No. 253,726

15 Claims. (Cl. 242—124)

This invention relates to a spool, reel or section beamhead, in which the head is made large in order that an increased amount of strand material may be wound upon the spool, reel, or beam, and has for one of its objects to provide means for strengthening the head in devices of this character.

Another object of the invention is to increase the strength of the head with very little additional weight.

Another object of the invention is to choose a location for strengthening of the head which will be extremely effective for the added weight supplied.

A further and more specific object of the invention is to locate the strengthening means at a greater radial distance from the axis of the barrel than the radius of the barrel.

With these and other objects in view, the invention consists of certain novel features of construction, as will be more fully described, and particularly pointed out in the appended claims.

In the accompanying drawing:

Fig. 1 is a side elevation of a section beam which incorporates my invention;

Fig. 2 is an end view thereof;

Fig. 3 is a fragmental sectional view on a somewhat larger scale than shown in Fig. 1;

Fig. 4 is a view similar to Fig. 3 but showing a modified form of construction;

Fig. 5 is an end view similar to Fig. 2 but showing the modified construction of Fig. 4;

Fig. 6 is a perspective view of the strengthening element used in Figs. 4 and 5;

Fig. 7 is a perspective view of the strengthening rib used in Figs. 4 and 5;

Fig. 8 is a sectional view on line 8—8 of Fig. 5, showing the attachment of the two members shown in Figs. 6 and 7;

Fig. 9 is a fragmental end view similar to Figs. 2 and 5, showing a still different modified form of arrangement of the structure.

In the textile industry, the tendency has been to increase the diameter of the heads of section beams or the like in order to enable a greater length of warp to be warped onto the beam. The increase in the diameter of the head has created a problem for strengthening the head against the stresses which are exerted by the warp when the beam is filled with yarn which is especially important when the yarn is formed from synthetic fibers, such as is known as rayon or the like. If these heads do not remain true on a warp beam, difficulty is experienced in the warping of the yarn. I have found that if a strengthening ele-

ment is placed between the head plate and the reinforcing plate and at a location outwardly with reference to the position of the barrel that a very remarkable increase in strength is provided in the head in its resistance to stresses and this is accomplished with very little increase in weight of the head. Further, by utilization of this character of strengthening, I can very readily strengthen the head between the bolts which tie the heads to the barrel, the location between the bolts being the weakest part of the head, and the following is a more detailed description of the present embodiment of this invention, illustrating the preferred means by which these advantageous results may be accomplished:

With reference to the drawing, 10 designates a barrel of a section beam although it will be readily understood that this may be the barrel of a spool or reel so far as this invention is concerned.

A head unit 11 is secured to each end of the beam 10 by means of the tie rods 12 extending through channels 13 in the barrel and passing through the head units where they are secured by nuts 14 on the threaded ends of the rods. I have illustrated five of these tie rods 12 and it will be readily understood that any suitable number may be provided. Wooden discs 15, 16 are doweled in position in the barrel 10 and an axially extending shaft 17 is supported by these discs assisted by means of the bearing member 18. This rod is threaded along the portion which extends through the heads and is reduced to provide trunnion ends 19 for supporting the section beam for rotation in warping or drawing off the warps therefrom.

The heads 11 are each a unit construction which may be attached bodily to the barrel and the shaft 17 just above described. Each unit 40 consists of a head plate 20 arranged with its inner surface at right angles to the axis for contact with the work. The reinforcing plate 21 is bowed outwardly so that it contacts the plate 20 where it is welded as at 22 while it is spaced from the head plate 20 at its middle portion as at 23.

The head plate 20 is deflected outwardly as at 24 and provided with a central opening in which fits a bushing 25 having a flange 26 beneath which there are washers 27 to assist in supporting the same. The bushing is welded to the head plate around the opening in portion 24 and also welded to the reinforcing plate. An opening 28 in the reinforcing plate 21 continues the opening formed by the bushing 25 and is of a size to

slide over the axle 17. A nut 29 engages the threads 30 of the axle to abut the reinforcing plate and assist in holding the head securely against the edge of the barrel 10 and also assists in supporting the axle. Bosses 31 having openings through which the tie rods 12 extend are welded to the head plate 20 and extend through reinforcing plate 21 and are welded to this reinforcing plate, so that when the nuts 14 are threaded onto the ends of the tie rods they abut these bosses carried by the head unit and assist in holding the head unit against the edge of the barrel.

In order to further strengthen the plates of the head unit, I provide a strengthening element 35 which, as illustrated in Figs. 1 to 6, is annular in form. This strengthening element is located at a greater radial distance from the axis of the barrel than the radius of the barrel 10 or, in other words, it is positioned further outwardly from the center of the head than the surface of the barrel. This location is of importance as it is found that a greatly increased strength is acquired in such location which is not present if this strengthening element is not positioned outwardly beyond the radius of the barrel. This strengthening element is welded as at 37 annually to the head plate 20 on both its outer and inner circumference and is welded at intervals to the reinforcing plate 21, such intervals of attachment being selected at locations 38 about midway between the attachment of the tie rods 12 to the head. This location serves to strengthen the head at the weakest point as it is between the tie rods that the head is most liable to be distorted because of stresses which are provided by the packaged yarn. These welds as at 38 are provided by an opening 39 in the reinforcing plate and a filling of this opening with welded material which attaches the annular strengthening element 35 to the reinforcing plate in a very firm manner.

In some cases it is desirable to provide some additional strength between the tie rod connections 14 and outwardly from them, and in this case I may deflect outwardly portions of the annular strengthening element as at 40 (see Fig. 9), so as to extend them a greater distance from the axle center, and in this case the welding means 38' will be located at the apex of the outward bulge for attachment purposes.

In some cases, instead of deflecting outwardly the annular member 35, ribs 41 (see Figs. 4 and 5) may be provided at the locations between the tie bolts 14, these ribs extending radially either inwardly from or outwardly from the annular strengthening element but preferably crossing the annular strengthening element as I have illustrated in Figs. 4, 5 and 8. This crossing is performed by notching the annular strengthening element 35' as at 42 and also notching the ribs as at 43 causing the two parts to fit together and be welded as at 44 as shown in Fig. 8.

By the arrangement here shown, a head is provided in which the weight is but very slightly increased and yet the strength is increased about 60% which is exceedingly important where heads are used of a large diameter. This arrangement enables the heads to be light and yet strong which is a very desirable feature.

The foregoing description is directed towards the construction illustrated, but I desire it to be understood that I reserve the privilege of resorting to all the mechanical changes to which the device is susceptible, the invention being de-

fined and limited only by the terms of the appended claims.

I claim:

1. In a section beam, spool, reel or the like, a barrel, a head unit secured at intervals to the barrel, comprising a pair of plates with one overlying the other and so arranged as to provide a space between them, and a strengthening element contacting said plates and located in said space and having an inner radius greater than the outer radius of the barrel, said element being generally circular, radial reinforcing ribs located in said space between the points of attachment of said head unit to said barrel and contacting said element and of a size to engage both of said plates.
2. In a section beam, spool, reel or the like, a barrel, a head unit secured at intervals to the barrel comprising a pair of plates with one overlying the other and so arranged as to provide a space between them, and a strengthening element contacting said plates and located in said space at a distance from the barrel axis greater than the outer radius of the barrel, said element being generally circular, radial reinforcing ribs located in said space between the points of attachment of said head unit to said barrel and extending inwardly and outwardly from said element and of a size to engage both of said plates.
3. In a section beam, spool, reel or the like, a barrel, a head unit secured at intervals to the barrel, comprising a pair of plates with one overlying the other and so arranged as to provide a space between them, and a strengthening element contacting said plates and located in said space at a distance from the barrel axis greater than the outer radius of the barrel, said element being generally circular, radial reinforcing ribs located in said space between the points of attachment of said head unit to said barrel and extending outwardly from said element and of a size to engage both of said plates.
4. In a section beam, spool, reel or the like, a barrel, a head unit secured at intervals to the barrel, comprising a pair of plates with one overlying the other and so arranged as to provide a space between them, and a strengthening element contacting said plates and located in said space with its inner radius at a distance from the barrel axis spaced from the outer radius of the barrel, said element being generally circular, radial reinforcing ribs located in said space between the points of attachment of said head unit to said barrel and having interlocking engagement with said element.
5. In a section beam, spool, reel or the like, a barrel, a head unit secured at intervals to the barrel, comprising a pair of plates with one overlying the other and so arranged as to provide a space between them, and a strengthening element contacting said plates and located in said space with its inner radius at a distance from the barrel axis spaced from the outer radius of the barrel, said element being generally circular, radial ribs located in said space between the points of attachment of said head unit to said barrel and contacting said element and of a size to engage both of said plates, said ribs being welded to said element and to one of said plates.
6. In a section beam, spool, reel or the like, a barrel, a head unit secured at intervals to the barrel, comprising a pair of plates with one overlying the other and so arranged as to provide a space between them, and a strengthening element contacting said plates and located in said

space with its inner radius at a distance from the barrel axis spaced from the outer radius of the barrel, said element being generally circular with portions projecting along the line of a radius extending outwardly between the points of attachment of said head unit to said barrel.

7. In a section beam, spool, reel or the like, a barrel, a head unit secured at intervals to the barrel, comprising a pair of plates with one overlying the other and so arranged as to provide a space between them, and a strengthening element contacting said plates and located in said space with its inner radius at a distance from the barrel axis spaced from the outer radius of the barrel, said element being generally circular with portions projecting along the line of a radius extending outwardly between the points of attachment of said head unit to said barrel, said outwardly extending portions being welded to said reinforcing plate.

8. In a section beam, spool, reel or the like, a barrel, a head plate at generally right angles to the axis of the barrel and provided with a central opening, a reinforcing plate having a central opening located concentrically of said first mentioned opening and having portions spaced outwardly from the head plate, a generally annular strengthening element contacting each of said plates and located in the space between said plates at a radial distance from the axis of the barrel greater than the outer radius of the barrel, a second strengthening member secured to said plates adjacent to said openings, and means extending radially outwardly from said generally annular member and in contact with said plates and secured to said reinforcing plate by welding.

9. In a section beam, spool, reel, or the like, a barrel, a head plate at right angles to the axis of the barrel and extending across and abutting the end of the barrel, a reinforcing plate spaced outwardly from the head plate centrally thereof and secured to the head plate at its periphery and also centrally thereof, and a strengthening element bridging the space between and contacting each of said plates at a radial distance from the axis greater than the outer radius of said barrel by an amount greater than the thickness of said element and welded to each plate to reinforce the head plate at this location.

10. In a section beam, spool, reel, or the like, a barrel, a head plate at generally right angles to the axis of the barrel and extending across the ends of the barrel, a reinforcing plate provided with a plurality of spaced openings and having portions spaced outwardly from the head plate, and a generally annular strengthening element contacting each of said plates and located in the space between said plates and aligned with said openings and at a radial distance from the axis greater than the outer radius of said barrel, said element being secured to said head plate by a weld about said element and to said reinforcing plate at said openings, and with the welding material extending into said openings.

11. In a section beam, spool, reel, or the like, a barrel, a head plate at generally right angles to the axis of the barrel, a reinforcing plate provided with spaced openings therein and having portions

spaced outwardly from the head plate, means positioned between said openings for securing said plates at intervals to the barrel, and a generally annular strengthening element contacting each of said plates and located in the space between said plates and aligned with said openings and at a radial distance from the axis greater than the outer radius of said barrel, said element being secured to said head plate by a weld about said element and to said reinforcing plate by welding material extending into said openings.

10 12. In a section beam, spool, reel or the like, a barrel, a head plate at generally right angles to the axis of the barrel, a reinforcing plate having portions spaced outwardly from the head plate, a generally annular strengthening element contacting each of said plates and located in the space between said plates at a radial distance from the axis of the barrel greater than the outer radius of the barrel, and means extending radially outwardly from said generally annular member and in contact with said plates and secured to said reinforcing plate by welding.

15 13. In a section beam, spool, reel or the like, a barrel, a head plate at generally right angles to the axis of the barrel, a reinforcing plate provided with spaced openings therein and having portions spaced outwardly from the head plate, means positioned between radial lines passing through said openings for securing said plates at intervals to the barrel, and strengthening means contacting each of said plates and located in the space between said plates and aligned with said openings, said means being secured to said head plate and to said reinforcing plate.

20 14. In a section beam, spool, reel or the like, a barrel, a head plate at generally right angles to the axis of the barrel, a reinforcing plate provided with spaced openings therein and having portions spaced outwardly from the head plate, means positioned between radial lines passing through said openings for securing said plates at intervals to the barrel, and radially extending strengthening means contacting each of said plates and aligned with said openings, said means being welded to said head plate and welded through said openings to said reinforcing plate.

25 15. In a section beam, spool, reel or the like, a barrel, a head plate at right angles to the axis of the barrel and extending across and abutting the end of the barrel, a reinforcing plate secured at its periphery to the head plate and having a conical portion spaced from the head plate in a central area thereof to provide a generally wedge shape cross-sectional space, means for connecting said plates at their central axis whereby a generally triangular formation of the plates and their central connection in cross section is provided radially outwardly, means about the axis of the barrel at spaced intervals for securing the plates to the barrel, and a generally annular strengthening element bridging the space between and contacting each of said plates at a radial distance from the axis greater than the outer radius of said barrel and said spaced securing means to reinforce the head plate at this location.

ROBERT V. OLSON.
